UNITED STATES PATENT OFFICE.

EDWARD J. WORDEN AND HENRY G. KASTLIN, OF LA CROSSE, WISCONSIN.

DRILL.

1,315,270.

Specification of Letters Patent. Patented Sept. 9, 1919.

Application filed February 8, 1919. Serial No. 275,724.

To all whom it may concern:

Be it known that we, EDWARD J. WORDEN and HENRY G. KASTLIN, citizens of the United States, residing at La Crosse, in the county of La Crosse and State of Wisconsin, have invented certain new and useful Improvements in Drills, of which the following is a specification.

This invention relates to improvements in drills and more particularly to devices or mechanisms for drilling holes in railroad rails and the like, when laid in the form of a track.

The principal object of this invention is the provision of such a mechanism which may be readily and securely set and clamped in position and is provided with a rotatable drilling tool with manual means for setting and automatic means for feeding.

Further objects of this invention include improvements in details of construction and arrangement, whereby a simple and effectively operating mechanism of this character is provided.

To the accomplishment of the foregoing and such other objects as may hereinafter appear, our invention consists in the construction, combination and arrangement of parts, hereinafter described, and then sought to be defined in the appended claims, reference being had to the accompanying drawing forming a part hereof and which show, merely for the purpose of illustrative disclosure, a preferred embodiment of our invention, it being expressly understood however that various changes may be made in practice within the scope of the claims without digressing from our inventive idea.

In the drawings

Figure 1 represents an elevational view of one of the sides, called the front side, of a mechanism constructed to embody our invention, shown in position for operation.

Fig. 2 is a view similar to Fig. 1, in elevation, and taken from the other side of the device, which we call the rear side.

Fig. 3 is an elevational view looking at one end of the device.

Fig. 4 is a horizontal transverse section taken substantially on line 4-4 of Fig. 1.

Fig. 5 is a horizontal sectional view taken substantially on line 5-5 of Fig. 1.

Fig. 6 is a vertical section taken through the drill operating and setting shaft and showing the operating and setting mechanism.

This invention is designed, primarily, to provide a manually operated mechanism, which is portable, and adapted to be set and clamped in position on a railroad rail and to drill holes on a vertical axis into and through the base of the rail, to receive spikes, bolts or other securing means. This mechanism includes a pair of vertically arranged frames designated by reference characters 10 and 11, respectively, the frame 10 supporting the driving mechanism and the frame 11 supporting the drill and its actuating and setting shafts. The frame 10 includes the vertically extending side members 12 which are connected by transverse members 13. Suitable bearings 14 are provided near the upper end or head of the frame 10 to receive the main power shaft 15 on each end of which is mounted the manually operated handle 16. On this shaft 15 is provided the bevel gear 17 which meshes with a similar bevel gear 18 on the upper end of the vertical shaft 19, which is journaled in suitable bearings 20 provided on the transverse members 13 of frame 10. On the lower end of this vertical shaft 19 we mount the driving gear 21. The lower ends of the side members 12 of the frame 10 are provided with substantially right angled extensions 22, by means of which the frames 10 and 11 are connected together. These frames are also connected together at an upper part by means of clamping bolts 23 (see Fig. 5 particularly).

Frame 11 includes side members 24 and transverse members 25, the transverse members 25 being provided with suitable bearings or journals 26 for the shaft parts to be hereinafter referred to.

The drill tool driving shaft 27 is journaled for rotation in the lower bearing 26 and is adapted to have secured to its lower end a suitable drill tool 28. This shaft 27 has a loose coupling 29 to the drill tool feeding and setting shaft 30, which is screw threaded, as shown, and is journaled in the upper bearings 26 of the frame 11. Shaft 27 is rotated by means of the gear 31 which meshes with gear 21 provided on the lower end of the vertical driving shaft 19. This gear 31 has a slidable connection with shaft 27 by means of a feather and spline, as shown, particularly in Fig. 6. A cam 31' is provided to rotate with said gear 31.

Shaft 30 is for the purpose of moving shaft 27 and drill tool 28 up or down, so that

the tool may be set properly prior to its actuation and then when actuated shaft 30 will operate to feed the tool properly into the material. This is accomplished by means of 5 the gear 32 which is threaded on the shaft 30.

Gear 32 meshes with gear 33 on the lower end of the vertical shaft 34 on the upper end of which is the actuating handle 35. This provides means for a comparative quick 10 raising and lowering of the shaft 30 and consequently drill tool 28 in setting the tool or in releasing the same from the work.

To feed the tool during the drilling operation, gear 32 is rotated step by step, 15 which results in a slow lowering of shaft 30 and drill tool 28, and this is accomplished by means of the dog 36 pivotally connected to an extension 37 of the vertical rod or shaft 38, a spring 39 being provided to permit the dog to click or idle in one direction.

This rod or shaft 38 is journaled in suitable bearings on one side of the frame 11 and at its lower end is provided with the arm 40 having on its end a roller which engages with 20 the cam 31' previously described as connected to gear 31 to move therewith. It is, therefore, seen that as the shaft 27 is driven by means of gear 31, cam 31' will engage the roller on the end of arm 40 and cause 25 the pawl or dog 36 to move the gear 32 a slight distance for each revolution and consequently move the shaft 30, step by step.

An important feature of this invention resides in the manner and means of supporting and clamping this mechanism in position for operation. A foot member 41 is secured to each side of the frame 11 and extends downwardly therefrom. This foot member has a toe part 42 which is adapted to fit between 30 the base and the under side of the head of the rail, a recess 43 being formed in the foot member to receive part of the head of the rail. This foot member is also provided with a shoulder 44 formed by said recess 43 which is adapted to rest on part of 35 the upper surface or tread of the head of the rail. These parts are fixed or secured immovably to said frame 11.

The coöperating clamping members are in 40 the form of foot members 45 which are pivotally connected, as at 46, to the lower end of the side members 12 of said frame 10. These foot members are likewise provided with the toe portion 46 which fits between 45 the base of the rail and the underside of the head, having the cut-out recess 47 for that purpose, and also for the purpose of providing the overhanging part or shoulder 48 which rests on top of the head or tread of 50 the rail, as shown. It is to be noted that the two foot members coöperate to provide means for completely embracing the web and head of the rail, and further that this means is duplicated so as to afford a 55 plurality of bearings at spaced apart dis-

tances, the drill tool operating between the sets of bearing and clamping members.

Each pair of foot members 41 and 46 are securely held in their clamping and locking position by means of the locking link 49, 70 these being in the form of loop members having the spaced apart side members 50 between which the foot members 41 and 46 are positioned, these side members 50 being provided with openings therethrough, 75 adapted to receive the locking wedges 51, the inclined sides 52 of which engage the foot members 46 and operate to force the parts together in secure clamping engagement with the rail. These wedge members 52 may 80 be secured to the mechanism by means of a chain or similar flexible connection 53 to reduce the liability of their loss.

In setting up the mechanism for operation, it is seen that the foot members 41 are 85 placed in position on one side of the rail and then the hinged foot members 45 are dropped in their proper position. The locking links 49 are then placed and locked in position by means of the wedge members 51, 90 as is well understood. The mechanism is then in position for operation and the drill tool may be lowered into engagement with the base of the rail by manually operating the handle 35 and when set, the actuating 95 handles 16 will be rotated which will cause the rotation of the drill tool and the automatic feeding of the same into the material.

It is, therefore, seen that we have provided a very simple and effective mechanism 100 for drilling holes on a vertical axis, preferably in the base of a railroad rail. This mechanism may be quickly and securely set up in position and just as quickly taken down or released from operating 105 position.

Having described our invention, what we claim is:—

1. A mechanism of the character described including in combination a supporting means 110 having a drill tool mounted therein on a vertical axis, driving means for actuating said drill tool, means for setting and feeding said drill tool, means for holding said mechanism in position on a rail including two 115 pairs of spaced apart foot members each having a part adapted to engage the rail on opposite sides thereof, said drill tool being disposed between said pairs of foot members, and means for clamping said opposed pairs 120 of foot members to opposite sides of and in contact with the vertical web of the rail.

2. A mechanism of the character described including in combination, a supporting means, a drill tool mounted therein on a 125 vertical axis, driving means for actuating said tool, means for setting and feeding said drill tool, and means for holding said mechanism in position on a rail, including a plurality of pairs of foot members arranged on 130

opposite sides of the rail and spaced apart, the drill tool being located between said pairs of foot members, each pair of foot members comprising one rigidly connected 5 to said supporting means and the other pivotally connected thereto, each foot member having a toe portion adapted to fit between the base and the under side of the head of the rail, each foot member also having a cut 10 out recess to embrace part of the head of the rail and to form a shoulder to overlie and rest upon the top surface or tread of the rail and a link extending over the top of the rail heads for clamping said opposed pairs 15 of foot members to opposite sides of the rail.

3. A mechanism of the character described including in combination, a supporting means, a drill tool mounted therein on a 20 vertical axis, driving means for actuating said tool, means for setting and feeding said

drill tool, and means for holding said mechanism in position on a rail, including a plurality of pairs of foot members arranged on opposite sides of the rail and spaced apart, 25 the drill tool being located between said pairs of foot members, each pair of foot members comprising one rigidly connected to said supporting means and the other pivotally connected thereto and means for 30 clamping said opposed pairs of foot members to opposite sides of the rail, said clamping means including a link member formed with spaced side portions adapted to embrace said foot members and having a wedge 35 connected thereto adapted to engage certain of said foot members to move them into engagement with the sides of the rail.

In testimony whereof we hereunto set our hands.

EDWARD J. WORDEN.
HENRY G. KASTLIN.
